UNITED STATES PATENT OFFICE

EDWIN F. BEUGLER, OF BUFFALO, NEW YORK, ASSIGNOR TO E & B HOLMES MACHINERY CO., OF BUFFALO, NEW YORK, A CORPORATION OF NEW YORK

BARREL-MAKING MACHINE

Original application filed January 31, 1927, Serial No. 164,676. Patent No. 1,723,838. Divided and this application filed May 29, 1929. Serial No. 366,899.

This invention relates to a machine for making slack barrels having a body composed of an annular row of longitudinal staves, each of which tapers toward its opposite ends, so that the completed barrel has a bilge midway of its length, and the several staves being held together by surrounding hoops.

It is the object of this invention to provide improved means for driving the hoops on the body or shell of the barrel.

This is a division of application No. 164,676, filed January 31, 1927, now Patent No. 1,723,838.

15 In the accompanying drawings:

Figure 1 is a vertical section of a barrel making machine embodying my invention and showing the bilge hoop driving jaws disengaged from the bilge hoop and the end hoop driving ring in engagement with the end hoop.

Figure 2 is a horizontal section taken on line 2—2, Fig. 1.

Figure 3 is a fragmentary horizontal section taken on line 3—3, Fig. 4.

Figure 4 is a fragmentary vertical section taken on line 4—4, Fig. 2.

Figure 5 is a fragmentary vertical section taken on line 5—5, Fig. 1.

20 Similar characters of reference indicate corresponding parts in the several figures of the drawings.

The staves 50 of this barrel shell or body are tapered from their central parts toward 35 their opposite ends, similar to those now commonly employed in slack cooperage, and these are temporarily held together adjacent to the bilge and the ends of the shell by bilge and end hoops 107, 106 respectively.

40 After the upper ends of the staves of the barrel have been drawn together or contracted by the windlassing mechanism so that the shell or body of the barrel is of substantially tubular form, but having a bilge

45 in its center, the operator places another temporary or trussing end hoop 106 on this end of the shell before releasing the windlassing rope and then loosely applies permanent bilge hoops 107 upon opposite ends of the 50 shell or body adjacent to the bilge thereof.

The shell having the temporary end hoops and the permanent bilge hoops applied thereto is then placed in an upright position with one end resting on the main base 75 in proper position relative to the 55 hoop trussing or driving mechanism which is constructed as follows:

Arranged above that part of the main base supporting the barrel to be trussed is a vertically movable cross head 108 which is secured on opposite sides to the upper ends of two vertically movable gear racks 109. The latter are guided at their lower ends in pedestals 110 which rise from the main base on opposite sides of the barrel body or shell supported on the base. These gear racks together with the parts mounted thereon are caused to rise and fall by a lifting mechanism of any suitable construction.

The mechanism whereby the trussing or driving of the bilge hoop is effected is constructed as follows:

The numeral 156 represents a plurality of upright driving arms which are arranged in an annular row around the cross head 108 and each of which is pivoted thereto at its opposite end by means of a horizontal pivot bolt 157 so that the driving die or jaw 158 at the lower end of each driving arm may be moved toward and from the periphery of the 80 barrel shell or body, and into and out of engagement with the upper edge of the upper bilge hoop. The several driving arms are moved inwardly preparatory to engaging with the bilge hoop during the descent of 85 the main cross head by means of a rotary crank disk 159 journaled to turn about a vertical sleeve 160 mounted vertically in line with the axis of the barrel shell when the same is in its normal operating position on 90 the main base 75.

This crank disk is provided with a plurality of crank pins 161 each of which is connected with the inner end of a shifting rod 162. The outer end of each shifting rod is yieldingly connected with one of the driving arms below the fulcrum of the latter by slidingly engaging the outer part of each rod 162 with its guide lugs 163 on the respective driving arm, and interposing a 95

spring 164 between the inner guide lug 163 and the inner side of a collar 165 on the respective shifting rod, as shown for example in Figs. 1 and 2. In Fig. 2, the crank disk 159 is shown by full lines at one extreme of its turning motion in which the driving arms 156 are expanded or moved outwardly. Upon turning the driving disk 159 by means of a handle 166 into the position shown by dotted lines in Fig. 2, the several crank pins 161 on this disk will cause the shifting rods 162 to draw the driving arms 156 inwardly and engage the periphery of the barrel immediately above the upper bilge hoop thereon.

Such inward movement of the several driving arms is limited by providing the main cross head 108 at one or more points on its periphery with a stop 167 adapted to be engaged with the adjacent driving arm 156 as shown in Fig. 3. The driving arms are yieldingly held either in the outer inoperative or in the inner operative position by means of a retaining device consisting of a retaining dog 168 adapted to be engaged with one or the other of two notches or seats 169 and 170 arranged circumferentially on the adjacent part of the cross head, said dog being arranged in a tubular arm 171 mounted to turn with the crank disk 159 and held yieldingly in a projected position by means of a spring 172 arranged in the tubular arm 171 and bearing at its opposite end against the retaining dog 168 and the bottom of this tubular arm, as shown in Figs. 2 and 5.

After the operator has turned the crank disk 159 so as to shift the driving dies or jaws into the proper position relative to the periphery of the barrel, the operator works the lever 133 so as to cause the main cross head to descend whereby the dies or jaws of the driving arms are caused to engage the upper edge of the bilge hoops and drive the same downwardly on the shell or body of the barrel until it is tight, after which the operator reverses the throw of the crank disk 159 and causes the driving dies or jaws 158 to be disengaged from the bilge hoop. Thereafter the operator again manipulates the controlling lever 133 so as to cause the main cross head to effect the second and final part of its downward movement for the purpose of engaging a driving ring or flange 173 with the upper edge of the upper temporary or truss hoop, as shown in Fig. 1.

This driving ring is formed on the inner lower part of a circular rim 174 which is secured to the underside of the main cross head 108. During the last step of this descending movement of the main cross head, the upper end of the barrel is centered by engagement therewith of a plurality of downwardly diverging centering fingers 175 secured to the lower edge of the supporting rim 174 and adapted to engage with the upper

peripheral edge of the barrel shell or body, as shown in Fig. 1. During the final portion of the downward movement of the cross head, the driving arms and the driving dies or jaws at their lower ends are disengaged from the adjacent bilge hoop and move idly downwardly beyond this hoop as shown in Fig. 1, so that only the driving ring 173 at this time performs any function.

After the bilge and end hoops have been driven on one end of the barrel shell the latter is reversed end for end and similar operations are performed on the other end of the barrel shell which is now uppermost, while the reversed finished end is now resting on the main base 75 of the machine.

Any suitable means can be provided for centering the barrel shell relative to the hoop driving mechanism.

For the purpose of permitting driving heads or rims 174 having driving rings 173 of different diameters to be employed for operating on barrels of different sizes or diameters, and permit of ready substitution of one driving ring 173 of one diameter for that of another diameter without disturbing the axial alignment, the following means are provided for connecting the head or rim 174 of the end hoop driving ring with the cross head and adjusting these parts relatively to each other.

Projecting laterally from opposite sides of the driving head or rim 174 are two adjusting arms 275 each of which is provided with a circumferential slot 276 and a vertical opening 277. Above each of these arms the cross head 108 is provided with a supporting arm 278 which is connected with the respective adjusting arm 275 by means of a bolt 279 passing through a radial slot 872 in the arm 278 and the slot 276 of the arm 275, as shown in Figs. 2, 3 and 4. Each of the supporting arms 278 is also provided with a downwardly projecting tapering centering pin 280 which enters the opening or eye 277 in the adjacent adjusting arm 275 of the driving head, as shown in Figs. 3 and 4.

Mounted in an annular row around each opening 277 on the respective adjusting arm 275 and preferably at different quarters of the circle are three radial adjusting screws 281 which bear against different parts of the periphery of the centering pin 280 and are held in their adjusted position by means of clamping nuts 282. In mounting the driving head on the carrier or cross head 108, this head is first loosely connected by means of the bolts 279 of the arms 278 with the carrier or cross head. The driving head is then adjusted circumferentially as well as radially in the proper direction for bringing the driving ring 173 into the proper axial alignment with the shaft 176 of the cutter mechanism, which is effected by turning the screws 281 in one di-

rection or the other while the same are in engagement with the centering pin 280.

After the parts have been properly aligned, the bolts 279 are tightened so as to maintain these parts definitely in this relation. If

5 now it is desired to remove the respective driving head 174 from the cross head and replace it by another driving head adapted for a different diameter of barrel, it only is necessary to remove the bolts 279 in order to release the respective driving head without however disturbing the adjustment of the radial bearing screws 281 relative to the centering pin 280. This permits this driving

10 head to be again replaced on the cross head by simply slipping the openings 277 of the adjusting arms 275 upwardly over the centering pins 280 and then applying the fastening bolts 279 and thereby bring the parts together again in axial alignment without the

15 necessity of any re-adjustment, whereby changes in the machine for operating on different diameters of barrels can be effected easily and quickly so that a considerable saving in time and cost of production is effected.

By constructing the centering pins 280 of downwardly tapering form it is possible to easily remove the driving head from the cross head, inasmuch as the adjusting screws 281 will readily disengage themselves from the centering pins 280, due to the tapering form of the latter, and re-engagement of the same is equally easy. This, however, would not be possible if the centering pins 280 were 20 of cylindrical form, inasmuch as the adjusting screws 281 would have a tendency to bind on the centering pins 280 both when assembling the parts or dis-membering the same in case the driving head is tilted slightly out 25 of its level position during this operation.

40 I claim as my invention:

1. A barrel making machine, comprising a base adapted to support a barrel shell to be operated upon, a vertically movable carrier 45 arranged above the base, a driving ring arranged below said carrier and adapted to engage the upper end of the shell and the upper end hoop, adjustable means for shifting said driving ring in a plane at right angles to the axis of the shell, comprising a rim carrying said ring and provided on opposite sides with adjusting eyes, centering pins arranged on said carrier and projecting downwardly into said eyes, and a plurality of adjusting screws mounted on different parts circumferentially of each eye and engaging said centering pins, and means for detachably connecting said carrier and rim.

2. A barrel making machine, comprising a 50 base adapted to support a barrel shell to be operated upon, a vertically movable carrier arranged above the base, a driving ring arranged below said carrier and adapted to engage the upper end of the shell and the upper end hoop, adjustable means for shifting said

driving ring in a plane at right angles to the axis of the shell, comprising a rim carrying said ring and provided on opposite sides with adjusting eyes, centering pins arranged on said carrier and projecting downwardly into said eyes, and a plurality of adjusting screws mounted on different parts circumferentially of each eye and engaging said centering pins, and means for detachably connecting said carrier and rim, consisting of circumferentially slotted lugs arranged on said rim, radially slotted arms on said carrier, and bolts passing through said lugs and arms.

3. A barrel making machine, comprising a base adapted to support a barrel shell to be operated upon, a vertically movable carrier arranged above the base, a driving ring arranged below said carrier and adapted to engage the upper end of the shell and the upper end hoop, means for detachably connecting said carrier and ring, and adjustable means for shifting said driving ring in a plane at right angles to the axis of the shell, comprising a rim carrying said ring and provided on opposite sides with adjusting eyes, centering pins arranged on said carrier and projecting downwardly into said eyes, and a plurality of adjusting screws mounted on different parts circumferentially of each eye and engaging said centering pins, each of said centering pins being tapered.

In testimony whereof I hereby affix my signature.

EDWIN F. BEUGLER.
